UNITED STATES PATENT OFFICE.

AUGUST G. FROMUTH, OF PHILADELPHIA, PENNSYLVANIA, ASSIGNOR TO JOHN DUNLAP & SON, OF SAME PLACE.

DESIGN FOR CARPET.

SPECIFICATION forming part of Design No. 28,882, dated June 14, 1898.

Application filed April 21, 1898. Serial No. 678,399. Term of patent 3½ years.

To all whom it may concern:

Be it known that I, AUGUST G. FROMUTH, a citizen of the United States, residing at the city of Philadelphia, State of Pennsylvania, have invented and produced a certain new and original Design for a Carpet, of which the following is a full, clear, and exact description, reference being had to the accompanying drawing, forming part of this specification.

My invention relates to the surface ornamentation of a woven carpet; and it consists of the design therefor, as illustrated in said drawing, the distinguishing features comprising flowers and leaves set upon sprays of delicate root-work, the whole group relieved by a fine damask ground effect. 15

I claim—

The design for a carpet substantially as herein shown and described. 20

In testimony whereof I have hereunto affixed my signature this 21st day of April, A. D. 1898.

AUGUST G. FROMUTH.
